UNITED STATES PATENT OFFICE.

JAY NOBLE EMLEY, OF NEW YORK, N. Y.

WORKMAN'S TIME-RECORDER.

SPECIFICATION forming part of Letters Patent No. 788,760, dated May 2, 1905.

Application filed April 15, 1898. Serial No. 677,679.

To all whom it may concern:

Be it known that I, JAY NOBLE EMLEY, a citizen of the United States, residing at New York, in the county and State of New York, 5 have invented certain new and useful Improvements in Workmen's Time-Recorders, of which the following is a description, reference being had to the drawings accompanying and forming a part of the same.

10 My invention has reference to employees' time-recorders, and especially to improvements in the devices for printing a record by means of the keys inserted. It has for its object to simplify the construction of such devices and to make the construction more durable and to attain greater accuracy of record in time-recorders.

To this end my invention consists, essentially, in the embodiment in a time-recorder 20 of one or more revoluble type disks or plates each provided with a series of stepped teeth with which the key engages to rotate the disks to bring the type character on the periphery of the said disk corresponding to the tooth engaged into the proper position when the printing mechanism is brought into operation.

The features of invention will be indicated in the claims to follow the description of the herein-shown form of apparatus embodying 30 my invention.

Reference is to be had to the accompanying drawings, forming a part of this specification, in which similar characters of reference indicate corresponding parts in all the figures.

35 The drawings show that part of a workman's time-recorder which includes the minute and hour printing wheels, the means for driving the same from the time mechanism, such as a clock, and one form of recording 40 mechanism embodying my invention.

Figure 1 is a front elevation of a time-recorder embodying my improvements with the outside casing, a portion of the frame, and the clock-movement removed. Fig. 2 is a side 45 elevation looking from the left of Fig. 1. Fig. 3 is a side elevation illustrating the time-printing wheels and the type-disks. Fig. 4 is a front elevation of the type-disk having the type characters on its periphery to print 50 "in" and "out." Fig. 5 is a side elevation

looking from the left of Fig. 4. Fig. 6 is a front elevation of a type-disk having the type characters on its periphery to print the numerals. Fig. 7 is a side elevation looking from the left of Fig. 6. Fig. 8 is a plan view of a 55 key adapted to engage teeth on three type-disks. Fig. 9 is a side elevation looking from the left of Fig. 8. Fig. 10 is a plan view of a key adapted to engage the teeth on two disks. Fig. 11 is a plan view of a key adapted 60 to engage a tooth on one disk. Fig. 12 is a detail perspective. Fig. 13 is a detail front view showing position of key-opening in relation to disks.

Referring to the drawings in detail, 1 represents the back frame of the machine, having a bearing for the rear end of a shaft 2. On this shaft 2 time-wheels 3 and 4 are mounted. The hour-wheel 3 preferably has around its periphery two sets of type characters, each 7c running consecutively from "1" up to "12," inclusive, and said wheel 3 is fixed to a concentric wheel 5, which meshes with a gear-wheel 6, which is supposed to be driven by some source of power in a step-by-step motion, so as to bring the correct type character on the wheel 3 up to the proper position relative to the hammer at the beginning of each hour. 75

It may in some cases be desirable to make 80 the hour-wheel a trifle wider and place on its periphery beside each character of one set of type characters the letters "A. M." and beside each character of the other set the letters "P. M.," so that the printed record will indicate in what part of the day the impression was made. 85

The minute-wheel 4 has around its periphery sixty type characters running consecutively from "00" up to "59," inclusive, and 90 is secured to the concentric wheel 7, which meshes with a gear-wheel 8, which is supposed to be rotated either continuously or in a step-by-step motion by some source of power, such as the time mechanism of a clock, so as to 95 bring the correct characters on the wheel 4 up to the proper position relative to the hammer to print in conjunction with wheel 3 the correct hour and minute of day.

On the shaft 2 are also independently mount- 100

ed one or more plates or fragments of disks 9 9' 9", which may be actuated by any suitable instrumentality. The radius of each of these disks is preferably the same as that of 5 the time-wheels 3 and 4. Between these disks I have placed washers 11 in order to insure freedom of motion. On the periphery of these disks are ten type characters representing the 10 ten numerals from "1" to "0," inclusive. In each of these type-disks is a hole or slot 12 for the admission of a number-key, such as 15 shown in Figs. 8 to 11, inclusive. One side 13 of this hole or slot is notched into steps to correspond with the type characters on the periphery, the rise or height of each step being 20 of any convenient measure, while the tread or width of each step must be such as to insure the disks being rotated sufficiently by the key at the time the hammer is released to have 25 the proper character in position to be struck by the hammer. The steps or notches are arranged eccentric to the axis of the shaft 2, on which the disk is mounted, and as the key is adapted, by means to be hereinafter described, 30 to be revolved or moved through a path concentric with said axis it will be seen that each key is adapted to engage with but one of the series of steps of each disk. There is a pin 35 14 in the frame 1 (see Fig. 12) which is bent over into a U shape. One arm serves as a stop or guide against which each of the disks rests, and between the other arm and each disk is a spring 15, which operates to retract the disk and retain it in the proper position after each 40 record. Another type-disk or fragment of disk 10 of the same radius as the others and having on its periphery type characters to print "in" and "out" is placed on the shaft 2. The side of this disk 10 has two steps constructed 45 to engage the number-key and be operated thereby in a similar manner to the other disks.

In the front case 1^a of the device there is a 50 revoluble disk 16, centered on the shaft 2. In this disk is a slot 17 as long as the width of the keys and as wide as the thickness of the number-keys. Each key, as shown in Figs. 8 to 11, is provided with a stop 18, which determines the distance which it can be inserted 55 into said slot in the disk 16 and is made of sufficient length beyond the slot on either side to permit of its engaging as many disks as there are numerals in the number which the key is designed to record.

55 In the present instance I use the type-numerals on disk 9 alone to represent units, I use the type-numerals on disks 9' and 9 in combination to represent units and tens, respectively, in two figure numbers, and I use the type-numerals on disks 9", 9', and 9 in combination to represent units, tens, and hundreds, respectively, in numbers of three figures.

It will be seen that the length of each key 60 will depend upon the number of numerals in

the number it is to record. The surfaces 19 on the faces of keys number "738" and "36" will engage with the surface 20 of the type-disk 9', and the surface 21 of number "3" key will engage with the surface 20 of the type-disk 9. It will be readily seen that a certain section of each key is capable of actuating one disk, and by properly notching the key within that section any desired type character on the corresponding disk can be 75 alined in front of the hammer for printing.

Both ends of each key are similarly notched with the exception of that section which actuates disk 10. This section of the key on one side of 18 is made so as to bring the type characters printing "in" into alinement, and the corresponding section on the other side is made so as to bring the type characters printing "out" into alinement. By the insertion of the proper end of each key the operator 85 may cause the record to indicate whether it was made on his coming in to or his going out from work.

In Figs. 1 and 2 I show a spring-actuated hammer 22. The impression to be taken from the time-wheels and type-disks may be affected by such hammer. The type and numerals on the disks and time-wheels can be inked, or a ribbon, such as 23, may be inserted between the hammer and the type characters, and the paper, such as 24, or card or other device to be printed on may be run or inserted between the hammer and the ribbon at the time of taking an impression. The hammer is drawn by hand or by means of a suitably-arranged pawl 100 25, which is adapted to engage the key as it is turned and to depress the hammer until the pawl is freed and the hammer thus allowed to strike a blow upon the paper, thereby imprinting thereon numerals and letters indicating not only the particular minute and hour 105 of time when the impression is made, but also the number and direction, either "in" or "out," of the operator.

The operation of the mechanism is as follows: Assuming that the parts are in the position shown in Fig. 1, the operator inserts one end of his key into the slot on disk 16 until the stop 18 touches the plate 16. By means of the inner portion of the key the revoluble key-supporting disk or carrier 16 is rotated, and the key is caused to engage with that one of the steps or notches 13 which is properly related to the printing character on the disk corresponding to the number or one of the figures of the number on the key. If the number of the key consists of two figures, it will be understood that two of the revoluble printing-disks will be engaged by the key. It will be seen that as the key-carrier 16 is 120 rotated in the manner above described the key will also engage with the disk 10 to move the proper character thereon into operative position and will also engage with the pawl 25. When the key has passed beyond or out 130

of engagement with the pawl 25, the proper characters on the printing-disks will be in operative position, and as the hammer is released by the disengagement of said pawl 25 it will be forced forward by its spring and caused to produce an impression of said alined characters upon the paper strip. It will be seen that by means of a pawl 26 working in a ratchet-wheel 27 on the end of a bobbin to which a strip of paper is attached this operation will also advance the paper each time to present to the type characters an unprinted clear space within which the record will be printed. After the hammer has struck the type characters the key is turned by the operator back to its original position and withdrawn from the slot in 16, and the mechanism is ready to be operated again.

What I claim is—

20 1. In a time-recorder, the combination of a revoluble type-disk provided with a series of eccentrically-arranged stepped teeth, and operating means adapted to engage said teeth to move the said disk to bring characters upon 25 its periphery into the printing-line.

2. In a time-recorder, the combination of a revoluble type-disk provided with a series of stepped teeth, operating means adapted to engage one of said teeth to move said disk, and 30 means to retain said type-disk against said operating means.

3. In a time-recorder, the combination of a revoluble type-disk provided with a series of stepped teeth, operating means independent of 35 the disk and adapted to engage one of said teeth for revolving the disk to bring the corresponding character into the printing-line, and mechanism for making a record from the said character.

40 4. In a recording mechanism, a revoluble printing-disk having a series of peripherally-arranged printing characters and a series of eccentric teeth arranged between its periphery and axis.

45 5. In a recording mechanism, the combination of a revoluble disk having a series of printing characters on its periphery and a series of eccentric teeth between its periphery and axis, and a removable key adapted to 50 move about the axis of said disk and engage with one of the teeth thereon to bring one of the printing characters into operative position.

55 6. In a recording mechanism, the combination of a series of type-carrying disks mounted to revolve independently about a common axis and each provided with a series of stepped teeth, and a series of independent operating devices each adapted to engage a tooth on 60 one or more of said disks and to rotate the engaged disks to bring a type on each into operative position.

7. In a recording mechanism, the combination of a revoluble type-carrying disk, having 65 a series of stepped teeth, a second type-car-

rier, 10, and an independent operating means adapted to engage with one of the teeth on the said disk and also with the carrier 10 to bring selected type on both into alinement.

8. In a recording mechanism, the combination of a series of independent revoluble type-carrying disks, a supplemental type-carrier, 70 10, and independent operating means adapted to engage one or more of said disks and also the supplemental carrier to bring type on said 75 supplemental carrier and on the engaged disk or disks into alinement.

9. In a recording mechanism, the combination with a type-carrying disk, of a supplemental type-carrier, and a removable key or 80 operating means having two sections each adapted to engage both said disk and supplemental carrier, both of said sections acting to adjust the disk into the same position and each adapted to adjust the supplemental carrier to a position different from that effected by the other section.

10. In a time-recorder, the combination of a revoluble type-disk provided with a series of eccentrically-arranged stepped teeth, a second 90 revoluble type-disk 10 and operating means adapted to engage said teeth to move said disks to bring characters upon their periphery into the printing-line.

11. In a time-recorder, the combination of 95 a revoluble type-disk provided with a series of stepped teeth, a second revoluble type-disk 10, operating means adapted to engage one of said teeth to move said disks, and means to retain said type-disk against said operating 100 means.

12. In a time-recorder, the combination of a revoluble type-disk provided with a series of stepped teeth, a second revoluble type-disk 105 10, operating means independent of the disk adapted to engage one of said teeth for revolving the said disk to bring the corresponding character into the printing-line, and mechanism for making a record from the said character.

110 13. In a recording mechanism, the combination of a revoluble disk having a series of printing characters on its periphery and a series of eccentric teeth between its periphery and axis, a separate disk 10 and a removable 115 key adapted to move about the axis of said disk and to engage with one of the teeth thereon to bring one of the printing characters into operative position.

14. In a recording mechanism, the combination of a revoluble type-carrying disk, a separate type-carrying disk 10 and independent means adapted to engage said disks, when turned about an axis extending parallel to the axis of the said disks and move the same to 125 bring one of the type thereon into operative position.

15. An identifying means for recorders, &c., comprising a plurality of type-carriers having printing characters, a key, and oper- 130

- ating selective devices on said printing-type carriers and key by the direct engagement of which the turning of said key turns a predetermined set of printing characters to printing position, substantially as described.
16. An identifying means for recorders, &c., comprising a plurality of type-carriers, each having printing characters and corresponding selective projections, and a key having selective projections to directly engage the corresponding projections of the printing-type carriers and turn the corresponding printing characters to printing position, substantially as described.
17. An identifying means for recorders, &c., comprising a plurality of type-carriers having printing characters, a rotatable and removable key, and coöoperating selective devices on said printing-type carriers and key, by the direct engagement of which the turning of said key turns a predetermined set of printing characters to printing position, said type-carriers and key rotating around a common axis, substantially as described.
18. An identifying means for recorders, &c., comprising a plurality of printing-type carriers arranged in axial alinement, each type-carrier having its periphery provided with printing characters and its body pro-
- vided with a recess, the peripheral wall of 30 which has a series of selective stop shoulders or projections corresponding to the printing characters and a key having selective projections adapted to travel in said recesses and engage the corresponding stop-shoulders, substantially as described.
19. An identifying means for recorders, &c., comprising a plurality of printing-type carriers having peripheral printing characters, recesses in said type-carriers, the peripheral walls whereof have a series of stop-shoulders to be engaged by the key in one direction and a terminal stop-shoulder to be engaged by the key in the other direction, a key provided with selective projections, one for 45 each printing-type carrier, to engage said shoulders, and means for limiting the rotation of one key in each direction, whereby full rotation of said key in one direction sets the corresponding characters in printing position 50 and full rotation of the key in the other direction returns all of the type-carriers to their normal position, substantially as described.

JAY NOBLE EMLEY.
